BAND APPLYING MECHANISM

George E. Gampp, Kenmore, N. Y., assignor to
 American Machine & Foundry Company, a corporation of New Jersey

Application July 24, 1948, Serial No. 40,532

12 Claims. (Cl. 226—80)

1

This invention relates to band applying machines, more particularly to mechanism for applying a flexible band over the neck of a container.

One of the main objects of the invention is to more positively and accurately place the band over the neck of the container.

Still another object of the invention is to mechanically grip one end of the band and thereby strip it from members whereon the band is partially expanded, and apply the band to the neck of a bottle whereby slippage of the band during stripping and application to the bottle neck will be avoided.

These and other objects not specifically mentioned may be obtained by the construction which will be hereinafter described.

In the accompanying drawings which form a part of this specification:

Fig. 1 is a fragmentary side elevation of a machine upon which a plurality of carriers, each having sleeve applying means of this invention incorporated therein, are operatively supported for applying sleeves to bottles;

Fig. 2 is a horizontal section thereof on line 2—2 of Fig. 1;

Fig. 3 is a fragmentary side elevation of a portion of a cam track embodied in the machine of Fig. 1 as seen from the opposite side thereof;

Fig. 4 is a horizontal section of a portion of the machine on line 4—4 of Fig. 1;

Fig. 5 is a fragmentary, transverse vertical section of one of the sleeve carriers;

Fig. 6 is a fragmentary vertical section thereof on line 6—6 of Fig. 5;

Fig. 7 is a front elevation of the lower portion of one of the sleeve carriers;

Fig. 8 is a sectional plan view thereof, taken approximately on line 8—8 of Fig. 7;

Fig. 8a is a fragmentary, rear elevation illustrating part of the mechanism seen in Figs. 7 and 8;

Fig. 9 is a fragmentary side elevation of the lower end of a sleeve carrier illustrating the sleeve engaging and applying means prior to an operation in which the sleeve is engaged thereby for movement to position a sleeve upon the neck of a bottle;

Fig. 9a is a horizontal section thereof on line 9a—9a, Fig. 9;

Fig. 10 is a similar view, illustrating an intermediate step in the movements of the parts in applying a sleeve to a bottle;

Fig. 10a is a horizontal section thereof on line 10a—10a of Fig. 10;

2

Fig. 11 is a side elevation, partly in section, illustrating the parts of Figs. 9 and 10 in the position in which a sleeve has been gripped in a manner for application of the sleeve to a bottle neck;

Fig. 11a is a horizontal section thereof on line 11a—11a of Fig. 11;

Fig. 12 is a view similar to Figs. 9—11 in which the sleeve engaging parts have been moved to the position in which a sleeve has been opened to circular form directly over a bottle neck;

Fig. 12a is a horizontal section thereof on line 12a—12a of Fig. 12;

Fig. 13 is a vertical sectional elevation of the parts illustrated in Fig. 12, wherein those parts have been moved to position the sleeve about the bottle neck;

Fig. 13a is a horizontal section thereof on line 13a—13a of Fig. 13.

It will be observed that Fig. 1 of the present application corresponds essentially to a portion of Fig. 8 of the copending application of H. G. Allen et al., S. N. 738,470, filed March 31, 1947, for Band Applying Machine. Likewise Fig. 2 is similar to Fig. 61 thereof, and Fig. 4 corresponds to Fig. 64 in that application.

In Fig. 1 the bottles or other containers B, to the necks of which sleeves are to be applied, may be advanced continuously in the direction of the arrow in spaced relation by a conveyor 20 having a horizontal run travelling along the top of the conveyor frame 22. The bottles B may be spaced apart on run 22 by suitable movable elements 24 corresponding to hold-back fingers 171 and 172 of the above mentioned application a distance apart corresponding to the distance apart of a plurality of sleeve carrying elements or carriers C which travel in an endless path about the machine. Further description of the conveyor 20 and elements 24 is deemed unnecessary since the construction and operation thereof is fully disclosed in the above mentioned application. It may be noted, however, that conveyor 20 travels at a higher speed than the elements 24, wherefore it slips on the bottoms of bottles B, thus urging them instantly into engagement with the elements 24.

The sleeves are applied to the carriers C in any suitable manner on the side of the machine opposite to that shown in Fig. 1. This operation is described in detail in the aforesaid application and need not be described herein. As illustrated in Fig. 1, the upper and lower end of each carrier C is operatively secured to upper and lower sprocket chains 26 and 28 which travel about sprockets 30 mounted on vertical shafts 32

supported in bearings 33 at opposite ends of the machine. Each shaft 32 is provided on a portion thereof above chain 26 with sprockets which carry a chain 34 driven by suitable means which is fully described in the aforesaid application. It should be noted that the bearings 33 are supported on lateral extensions of a standard 36 corresponding to the standard S shown in said application.

Each sleeve carrier C, of which there may be 12 in the embodiment of the invention illustrated, includes a pair of parallel spaced upright rods or supports 40 to the upper ends of each pair of which is secured a member 42 operatively attached to the upper sprocket chain 26. The 15 lower ends of the rods 40 have secured thereto supporting members 44 by which they are attached to the lower sprocket chain 28. Below the members 42 on each pair of rods 40 there is secured thereto a bracket 48 supporting a roller 50, Fig. 1. Each pair of rods 40 also supports a vertically movable slide 52 at the rear of which is mounted a roller 54, Fig. 1. Between movable element 52 and bracket 48 and surrounding one of the rods 40 is a coil spring 56 the use of which will be hereinafter explained.

Each sleeve carrier C (see Figs. 5 and 7) is provided with a pair of pendant fingers 60. The front or outer finger 60 is secured to the lower end of a connector or adaptor 62 which may be secured at its upper end to a pendant arm 64 which is pivotally mounted on a stud 66 journaled in spaced outer and inner bearing portions 68 and 70 of the member 44 before mentioned. The inner or rear finger 60 is fastened to an adaptor 72 secured to another pendant supporting arm 74 which, like the arm 64, is similarly pivoted on another stud 67 supported by bearing portion 78 and another outer bearing portion 68 of the member 44. The arms 64 and 72 are mounted on the two shafts 66, which are arranged in axial alignment, to simultaneously swing inwardly and outwardly toward and away from each other. For controlling the in and out movement of the fingers 60 the arms 64 and 74 are each provided with a roller or cam follower 76 mounted to operatively engage oppositely inclined faces 78 of a tapered cam or wedge 80 fixed to the lower end of a rod 82 which is slidably mounted in member 44 and is fixed at its upper end to the slide 52 to reciprocate vertically therewith. Contact between the rollers 76 and the cam member 80 is assured by a tension spring 84, Fig. 5, which at its opposite ends is suitably secured to adaptors 62 and 72. When the cam member 80 is moved upwardly the fingers 60 are urged by the spring 84 towards each other so that their inner faces are closely adjacent. It is in the foregoing position, which occurs only on the side of the machine opposite to that shown in Fig. 1, that this action occurs. It is here that the limp and partially opened band or sleeves D are slipped upwardly onto the lower ends of the collapsed fingers.

However, the sleeves could also be applied by hand. Automatic mechanism, similar to that described in the above mentioned application, causes the fingers to be spread apart by downward movement of the cam 80 to an extent sufficient to cause the sleeves to be retained on the fingers.

The fingers 60 may be releasably locked in closed position during the application of a sleeve thereto by suitable mechanism illustrated in Fig. 5. This mechanism includes the latch 86

5

pivoted at one end to the adaptor 72 and having adjustably secured in its free end a stop screw 88. Intermediate its ends latch 86 has a notch 90 into which, in the closed position of the fingers 60 a lug 92 on the lower end of arm 64 may seat. In actual practice the sleeve is applied to the fingers by upward movement of a pair of suction blocks or members (not shown) similar to the suction pads 512 of the above mentioned application. At the time when these blocks arrive at a position where it is desired to apply the sleeve to the fingers the upper end of one of said blocks strikes stop screw 88 thereby raising and releasing latch 86 from lug 92.

It will be recalled that spring 56 surrounding one of the carrier rods 40 exerts downward pressure against the slide 52. Since rod 82 carrying cam 80 is fixed to slide 52, the cam wedge 80 will be moved downwardly through the action of spring 56 between rollers 76 to cause the fingers 60 to be spread apart to engage and support the sleeve as soon as the latch has been released. The extent to which the fingers 60 are opened during the foregoing step of applying the sleeve is controlled by the engagement of roller 54 on each carrier C with the upper edge of a horizontal cam bar 100 (see Fig. 1). As soon as the carrier leaves the sleeve applying station or zone the roller 54 travels to a lower portion 102 of cam bar 100 (Fig. 1) where, through action of cam wedge 80, the fingers 60 open to a greater extent to draw the sleeve taut and thereby retain it more securely on the fingers 60. In this position the fingers will approximate the location thereof shown in Figs. 5, 9a and 11a. This position is such that parts of the sleeve gripping and applying mechanism, which will be presently described, can move to positions between the fingers 60 to effect the necessary sleeve gripping operation.

40 A suitable embodiment of mechanism for gripping the lower edge of a band D to remove it from the fingers 60 and apply it to the neck of a bottle B will now be described. Referring to Figs. 9a and 10a of the drawings, it will be noted that the sections of a sleeve D which extend between a pair of opposed fingers 60 are drawn taut and straight. The gripping mechanism operates to grip opposite faces of the lower edges of such straight sections of a sleeve D, as illustrated in Figs. 11 and 11a, to draw these straight sections outwardly so that they will, with the parts of the sleeve which are engaging the outer faces of the fingers 60, assume a substantially cylindrical form of a diameter at the lower section of the sleeve which is somewhat greater than the diameter of the bottle top to which it is being applied, as illustrated in Figs. 13 and 13a. Each sleeve gripping mechanism forms a part of a carrier C and is mounted on a slide 110 which is reciprocable on the lower portions of the carrier rods 40 below part 44 (see Figs. 7 and 8). On portions of the slide 110 projecting outwardly beyond the rods 40 there are provided a pair of forwardly extending integral bearing sleeves 112. In one of these sleeves is mounted a pivot stud 114 whose forward end supports a pendant arm 116. In the other bearing sleeve 112 is mounted a pivot stud 120 to the forward end of which is clamped the upper end of a pendant arm 122. The front end of stud 114 has rigidly fixed to it a plate or clip 124 the lower end of which is bent rearwardly at 126, Fig. 7, and through which extends a bolt 128. One end of bolt 128 is threaded into a lug 130 on the adjacent arm 116. Between part 126 of clip 124 and the lug 130 is a compres-

sion spring 132 acting to urge part 126 away from lug 130 whereby adjustment of arm 116 relatively to arm 122 may be effected by screwing thumb nut 129 on the bolt 128 in or out and locking it in adjusted position by a cock nut 131, see Fig. 7.

Referring again to arm 116 it will be noted that it is provided with an angular portion 136 projecting from the hub portion thereof and constituting therewith a bell crank pivoted on stud 114. Similarly arm 122 has an angular extension 138 projecting from its hub portion and constituting therewith a bell crank movable about stud 126. Attached to the free ends of extensions 136 and 138 is an adjustable connecting rod 140. To the lower ends of arms 116 and 122 are secured gripper blocks 144. The under face of each block is under cut and has fastened thereon a sleeve engaging member 146. Each member 146 has an upstanding arcuate flange or section 148 the curvature of which approximates the curvature or outside diameter of the top portion of a bottle to which a sleeve is to be applied. The bottles may be of various configurations and may either have a cork within the neck or a cap surmounting the top. In a transverse direction the flanges 148 are of less width than the space between a pair of opened fingers 60 so as to be able to pass in between those fingers, as shown in Fig. 10a.

As shown in Figs. 11a, 12a, 13, and 13a, each block 144 has formed therein a longitudinal bore 150 in which is slidably mounted a plunger 152. The outer end of each plunger 152 has a head 154 which is reciprocable in a chamber 156 the outer end of which is closed by a circular diaphragm or flexible member 158 held in position by a closure plate 160. Between the inner face of head 154 and a shoulder 162 formed in chamber 156 is arranged a coil spring 164 which surrounds the plunger and urges it outwardly so that its inner end will be disposed within the bore 150 or aligned with the adjacent wall of the block 144 as shown in Fig. 13. Plungers 152 may be actuated by fluid pressure, such as compressed air, to cause them to move inwardly or toward each other to engage and deflect inwardly the intervening portions of the lower edge of a sleeve extending between the fingers 60 and thereby clamp such portions between the plunger ends and the outer faces of the gripping flanges 148 after said flanges have been moved upwardly into the sleeve, in a manner which will be hereinafter explained. Compressed air may be conducted into chamber 150 to deflect diaphragms 158 in any suitable manner. For example, as shown in Fig. 13 of the drawings, the lower ends of a pair of flexible hoses 170 are connected to an inlet pipe 172 secured in one of the closures 160 and communicating with a notch 174 in the closure 160 to thereby conduct air to the outer faces of the diaphragms 158 in the area back of the plunger head 154. The opposite or upper end of each hose 170, see Figs. 1, 5 and 6, connects with the ends of a transverse passage 176 in the part 44 which connects the carriage with the lower chain 28. The passage 176 is in communication with an upright passage 178 which may, for example, be formed in one of the upright rods 40 and leads to the top of the rod. Here the passage is in communication with one end of a flexible hose 180. The other end of each hose 180 is connected to duct 182 formed in a rotary valve head 184 mounted at the top of the standard 36.

The number of flexible members 180 and ducts

182 corresponds to the number of carriers C in the installation, and the rotary valve head 184 is arranged to travel at the same rate of speed as that of the carriages through their connection with the chains 26 and 28. Thus at each complete rotation of a carriage about the machine its duct 182 passes into and out of communication with a segmental part (not shown) in a stationary valve 186 underlying valve head 184, through which compressed air may be delivered at an appropriate time and duration for actuating the plungers 152 to operatively engage a sleeve as stated. Since the construction of the stationary valve corresponds to the structure of the stationary valve 616 of the aforesaid application, further description thereof is deemed unnecessary except to state that compressed air is supplied to the segmental part in member 186 by a supply pipe 188.

As illustrated in Fig. 1, there is mounted on the rods 40 of each carriage directly below the slide 52 thereof, another slide 190 on which is supported a roller 192 which in the travel of the carriage about the machine engages with the upper face of a cam track designated generally by the reference 194, see Fig. 2. As shown in full lines in Figs. 2 and 3, and in broken lines in Fig. 1, cam track 194 is provided on the side of the machine opposite to that illustrated in Fig. 1 with a cut away portion or notch 196. This track is also provided, as shown in detail in full lines in Fig. 1, with an inclined cam section 198 at the lower end of which is a short horizontal section 200 followed by an oppositely inclined section 202. Sections 198, 200, and 202 may be supported on a vertically adjustable support 204 for adjustment with respect to the main track portion 194, to enable those sections to be shifted up and down to allow the sleeve gripping mechanism to appropriately function with bottles of different heights.

In order to enable the sleeve gripping mechanism to engage the sleeves on the fingers 60, stretch them to the form shown in Figs. 12a and 13a, lower the sleeves down upon and release them on the bottle necks and then effect the return of the gripping mechanism to normal position, the following mechanism may be provided. A lower cam track structure (Figs. 1 and 4) is designated generally at 210. At the rear of the machine as viewed in Fig. 4, cam track structure 210 is provided with a horizontal section 212 having inwardly curved end portions 214 and 216. This section is fixed to the standard 36. Extending from the end 214 of section 212 is a track portion 218 which is located slightly inward of the track section 212. Part 218 connects with a curved cam plate 220 concentrically disposed about the adjacent shaft 32 and secured to the lower end of the bearing member 33. The other end of the bar 222 is connected to a curved plate 224 similarly mounted about shaft 33 at the opposite end of the machine. As shown in Fig. 4 there is formed at the connection between parts 222 and 224 a cam recess 226 for a purpose which will be hereinafter explained. It will be seen in Figs. 1 and 4 that the outer or front side of cam track 210 is provided with cam track sections 228 and 230 formed of vertical plate sections, the latter being at a somewhat greater distance from the standard 36 than is the section 228. Sections 228 and 230 are connected by a somewhat abrupt incline 232 on one end of section 230. The ends of sections 228 and 230 overlap relatively short track sections 234 and 236 which are secured to the adjacent cam plates 224 and 220. The cam sections 228 and

230 may be suitably supported on the standard 36 as shown in Fig. 4.

For controlling the movements of the arms 116 and 122, which support the sleeve gripping elements at their lower ends, there is provided a cam follower or roller 240 (see Figs. 1, 8 and 8a). Roller 240 is mounted at the free end of one arm 242 of a bell crank lever pivotally mounted on a shaft 244 supported on one of the sleeves 112. The other arm 246 of the bell crank has a pivotal connection 248 with one end of an adjustable connecting link 250. The other end of this link is similarly connected at 252 to the lower end of an arm 254 fixed to the rear end of the pivot stud 114. Mounted on the upper end of pivot shaft 244 is an arm 256 which carries at its free end an adjustable stop screw 258. This stop screw is engageable with a stop 260 on the adjacent bearing sleeve 112 and, when in contact therewith, as illustrated in Fig. 8, limits the number movement of the sleeve gripping members to thereby prevent those members from engaging each other in the travel of the carriage when, for example, the roller 240 might be riding free of the cam structure 210. Thus by manipulation of the stop screw 258 on each carrier C individual adjustment of the inner position of the gripping elements at the lower ends of arms 116 and 122 may be effected to assure uniform travel of these elements on all of the carriers.

Referring now to Fig. 8a, it will be observed that a link 262 has one end thereof pivoted at 264 to the rear face of slide 110 and at its opposite end is similarly connected to slide 190. This link thus provides means whereby the movements of slide 190 up and down rods 49 effects similar motion of slide 110 in accordance with the position of roller 192 on slide 190 as it travels about the cam structure 194. Assuming the cam follower 192 of a carriage C is travelling to the right on Fig. 2, the gripping elements will be opened with respect to a sleeve on a pair of fingers 60, approximately as indicated in Fig. 7. As soon as the follower 192 reaches the cam notch or recess 196 the structure including slides 190 and 110 will travel downwardly on rods 49 a distance such as will enable the top edges of flanges 148 of the gripping means to descend to a plane below the bottom edge of a sleeve as shown in Fig. 9. While roller 192 is still within the notch 196 of the cam structure 194, roller 240 will enter cam notch 226 of cam structure 210, thereby effecting simultaneous inward motion of the gripping elements to the position in Figs. 10 and 10a so that the flange portions 148 will be disposed below and within the portions of the sleeve intermediate fingers 60. This motion is effected through the swinging of pivot 248 of the bell crank about pivot 244 and the consequent swinging of arm 254 about stud 114 through the connecting link 250. This action results in inward movement of arm 116 about stud 114 through the before mentioned construction and arrangement of these parts. Since arm 116 is provided with the integral arm 138 this arm will also move and through the connecting rod 140 will effect similar movement of arm 138 and thereby impart motion to arm 122 but in the opposite direction.

As the carriage C continues to travel, the roller 192 thereon will move upwardly out of notch 196 of cam structure 194, causing a return or upward movement of slides 190 and 110 and carrying the gripper flanges 148 upwardly within the sleeve, as shown in Fig. 11. At this point, compressed

7
8
air operates to engage the plungers 152 with the intervening portions of the sleeve to thereby press these portions of the sleeve into gripping contact with the flanges 148. The carrier continues to travel, and in so doing the roller 240 leaves the notch 226 and travels about the articulate section 224, retaining the parts in position shown in Fig. 11. Eventually the carriage will arrive at the front of the machine and the cam follower 240 in travelling from the part 224 to a position against the front of part 210 rides a slight incline 270 which, through the movement of roller 240, causes the gripping mechanism to be separated to the position indicated in Fig. 12 where the flanges 148 have carried the lower portion of the sleeve outwardly to the position shown in 12a in which clearance between gripping mechanism and the fingers 60 is effected. The sleeve is thus gripped and expanded preparatory to lowering it over a bottle neck to the position shown in Fig. 13.

Continued travel of a carrier C will carry the roller 240 along the face of cam section 228, while at the same time the roller 192 on that carrier, having travelled along the corresponding horizontal portion of cam structure 194 will arrive at and travel downwardly on the inclined section 198 thereof. This downward travel causes the gripping mechanism to lower a gripped sleeve to the position of Fig. 13. When the sleeve has been lowered to its intended position the compressed air is released, causing retraction of the plungers 152 to free the sleeve from the gripper mechanism. Continued travel of the roller 192 to the lower end of incline 198 serves to carry the flanges 148 below the lower edge of the sleeve. At this time the cam follower 240 will engage the incline 232 of cam structure which will cause the arms 116 and 122 to swing about their pivots to carry the flanges 148 outwardly beyond the sleeve for needed clearance during return or upward travel of the gripping devices. During the foregoing retraction of the flanges 148 the roller 192 on the carrier will travel across the short cam section 200 to give the necessary dwell for clearance, after which it engages and moves upwardly over the reversely inclined section 202 to elevate the parts to their upper positions. During this travel and for a period thereafter follower 240 travels along the face of cam section 230 to retain the grippers in their open position, just described. In the continued travel of the carriage the follower 240 will ride over cam portions 236, 228 and 218 while returning to the cam section or track 212 at the rear of machine. It may be noted that the width of cam track sections 228 and 230 is sufficient to provide contact of roller 240 therewith during vertical movement of the gripping means.

While in the foregoing disclosure, the invention has been shown in connection with mechanism for moving the sleeves downwardly and upon containers traveling horizontally, the invention may be modified within the scope of the present invention to cause upward movement of the containers into the opened sleeves while such opened sleeves are held stationary or are carried horizontally on the carriers.

70 What is claimed is:

1. In a machine for applying a collapsible banding sleeve to a container, the combination with means for holding open a banding sleeve, a support for holding the containers in position to receive a banding sleeve, of sets of opposed grippers

coacting to positively grip one end of a sleeve held by said means, each of said grippers having an inner and outer member adapted to grip an intervening end edge of said sleeve, and mechanism for operating said grippers to grip said end edge of the sleeve held opened by said means and move said grippers to position said sleeve over one end of a container on said support.

2. In a machine for applying a banding sleeve to a container, the combination with means for opening a collapsed banding sleeve; of sets of opposed grippers coacting to grip one end of a sleeve opened by said means; and mechanism for operating said grippers to grip one end of the sleeve opened by said sleeve-opening means and move said sleeve over one end of a container; each set of grippers comprising an inner gripper arranged to enter one end of the sleeve opened by said means, and an outer gripper arranged opposite said inner gripper and adapted to engage the exterior face of the intervening end of the sleeve; and said gripper-operating mechanism including members for inserting said inner grippers into one end of the opened band and devices for moving said outer grippers to press against the intervening end of the opened band whereby said end of the band will be gripped between the inner and outer grippers while the opened band is retained on said means.

3. In a machine for applying a banding sleeve to a container, the combination with means for opening a collapsed banding sleeve, of sets of opposed grippers coacting to grip one end of a sleeve opened by said means, and mechanism for operating said grippers to grip one end of the sleeve opened by said sleeve-opening means and move said sleeve over one end of a container; each set of grippers including an inner gripper having an arcuate shape and arranged to enter one end of the sleeve opened by said means, and an outer gripper movably mounted to press the intervening end of said band against said inner gripper; and said gripper-operating mechanism including members for moving said inner and outer grippers outwardly whereby said band will be expanded to a predetermined extent to facilitate application thereof to the container to which said band is to be applied.

4. In a machine for applying a banding sleeve to a container, the combination with means for opening a collapsed banding sleeve; of sets of opposed grippers coacting to grip one end of a sleeve opened by said means; and mechanism for operating said grippers to grip one end of the sleeve opened by said sleeve-opening means and move said sleeve over one end of a container; each set of grippers including an inner gripper having an arcuate shape and arranged to enter one end of the sleeve opened by said means, and an outer gripper adapted to press the intervening end of said band against said inner gripper; and said gripper-operating mechanism including members for moving said inner and outer grippers outwardly whereby said band will be expanded to a predetermined extent to facilitate application thereof to the container to which said band is to be applied, and instrumentalities for moving said members downwardly with said grippers to apply the expanded band to one end of a container.

5. In a machine for applying a banding sleeve to a container, the combination with a support for holding the containers in position to receive a banding sleeve, sets of grippers coacting to positively grip one end of a banding sleeve internally

and externally; of mechanism for operating said grippers to grip one end of a banding sleeve, and means to move said grippers to expand the gripped sleeve to a predetermined size and shape and then move said sleeve over one end of said container on said support.

6. In a machine for applying a banding sleeve to a container, the combination with sets of grippers coacting to grip one end of a banding sleeve; of mechanism for operating said grippers to grip one end of a banding sleeve, expand the gripped sleeve to a predetermined size and shape, and then move said sleeve over one end of a container; each set of grippers comprising an inner gripper arranged to enter one end of a banding sleeve, and an outer gripper arranged opposite said inner gripper and adapted to engage the exterior face of the intervening end of the sleeve; and said gripper-operating mechanism including members for inserting said inner grippers into one end of the band and moving said outer grippers into a position opposite the inner grippers, and a pneumatically operated device for pressing said outer grippers against the intervening end of the band whereby said end of the band will be gripped between the inner and outer grippers.

7. In a machine for applying a banding sleeve to a container, the combination with sets of grippers coacting to grip one end of a banding sleeve; of mechanism for operating said grippers to grip one end of a banding sleeve, expand the gripped sleeve to a predetermined size and shape, and then move said sleeve over one end of a container; each set of grippers including an inner gripper having an arcuate shape and arranged to enter one end of the sleeve, an outer gripper movably mounted to press the intervening end of said sleeve against said inner gripper, and a ledge connecting said inner gripper and outer gripper and adapted to support the adjoining end of said sleeve; and said gripper operating mechanism including members for moving said inner and outer grippers outwardly with said ledges, while gripping the sleeve, whereby the sleeve will be expanded to an approximately cylindrical shape having a diameter slightly greater than the portion of the container to which said band is to be applied, and instrumentalities for moving said members downwardly with said grippers and ledges to apply the expanded sleeve to one end of a container.

8. In a machine for applying a banding sleeve to a container, the combination with a support for holding the containers in position to receive a banding sleeve, spaced sets of grippers coacting to grip the edges of one end of a banding sleeve; each set of grippers comprising an inner member and an outer member, the inner member engaging the inner surface of said sleeve and the outer member engaging the outer surface of said sleeve, of mechanism for operating each of said grippers to grip the intervening edge of one end of a banding sleeve between said inner and outer members and to move said grippers to position said sleeve over one end of a container on said support.

9. In a machine for applying a flexible banding sleeve to a container, a support for holding the containers in position to receive a banding sleeve, means for supporting an opened sleeve, sets of pincer-like grippers having inner and outer members co-acting to grip an intervening edge of one end of such opened sleeve between said inner and outer members, and mechanism for effecting gripping action of said opposed grippers to

11

grip said end of said opened sleeve and means to move said grippers to apply said sleeve to said container.

10. In a machine for applying a flexible banding sleeve to a container, a support for holding the containers in position to receive a banding sleeve, means for supporting an opened sleeve, opposed grippers each having members movable toward and away from each other and co-acting to positively grasp an intervening end edge of such opened sleeve, mechanism for effecting gripping action of said grippers to grip said open end of said sleeve, and means for effecting relative movement between said mechanism and said support to place said sleeve into position about a 15 container on said support.

11. In a machine for applying a banding sleeve to a container, the combination with a support for holding the containers in position to receive a banding sleeve, opposed sets of grippers, each set being operative to grip an intervening edge of a banding sleeve and said sets being mounted for movement toward and away from each other set; of mechanism for operating said grippers to grip an edge of a banding sleeve, and comprising adjustable cam means to move said movable sets of grippers away from each other to expand a sleeve gripped thereby to control the extent to which said grippers are moved apart and adjustable to vary the predetermined movement of 20 said grippers and move said grippers and said sleeve over one end of a container on said support.

12. In a machine for applying a banding sleeve

5
10

to a container, a support for holding the containers in position to receive a banding sleeve, a plurality of grippers, each of said grippers being adapted to grip the inside and outside of an intervening end edge of a banding sleeve; of mechanism for operating said grippers to grip an intervening edge of a banding sleeve, said plurality of grippers being circularly spaced one from the other, and comprising adjustable cam means to move each of said plurality of grippers in a radial direction toward and away from each other a predetermined distance for a predetermined adjustment of said cam to expand a banding sleeve held thereby to a specific predetermined size to fit over said container whereby different sizes of bands and containers may be accommodated.

GEORGE E. GAMPP.
